[57] CLAIM

The ornamental design for housing for a wall clock, as shown and described.

DESCRIPTION

FIG. 1 is a front elevational view of a housing for a wall clock showing my new design;

FIG. 2 is a left side elevational view thereof, the right side being a mirror image thereto;

FIG. 3 is a top plan view thereof, the bottom plan being a mirror image thereto; and

FIG. 4 is a rear elevational view thereof.

FIG. 1

FIG. 2

FIG. 3

FIG. 4
